UNITED STATES PATENT OFFICE.

LEANDER A. COGSWELL, OF MANCHESTER, NEW HAMPSHIRE, ASSIGNOR TO LACENE MANUFACTURING COMPANY, OF MANCHESTER, NEW HAMPSHIRE, A CORPORATION OF MAINE.

AUTOMATIC GATE-CONTROLLING AND MARKER-TRIPPING MECHANISM.

1,366,889.

Specification of Letters Patent. Patented Jan. 25, 1921.

Application filed March 20, 1918. Serial No. 223,679.

To all whom it may concern:

Be it known that I, LEANDER A. COGSWELL, a citizen of the United States, and resident of Manchester, in the county of 5 Hillsboro and State of New Hampshire, have invented an Improvement in Automatic Gate-Controlling and Marker-Tripping Mechanism, of which the following description, in connection with the accompanying drawings, is a specification, like letters on the drawings representing like parts.

My present invention is an improved machine of the type of evening, grading and marking machines illustrated in the U. S. 15 patents to Elmer P. Nichols, such for example as Reissue No. 12,288, dated November 22, 1904, and No. 841,809, dated January 22, 1907, upon evening and grading machines. The object of the invention is to 20 improve and perfect machines of this type, particularly with reference to the gate controlling and marker or stamp tripping mechanism, as shown in E. P. Nichols Patent, No. 1,104,378, dated July 21, 1914.

As herein illustrated, I have shown the invention embodied in the well-known Nichols grading machine for grading stock and marking it in accordance with its grade, but it will be understood that the improvement 30 in the gate controlling, opening, closing and locking mechanism is not limited to machines for grading and marking, but is equally applicable to machines for cutting, trimming and evening the sole in accordance with the grading mechanism. 35 Therefore, the invention applies to both evening and grading machines, evening and marking machines, and the grading, evening and marking machines, being illustrated 40 with a grading and marking machine for simplicity of the drawings and clearness of description.

Important features of the invention consist in mechanism for controlling the gate; 45 in improved arrangements affording a greatly increased range for raising and lowering the opening gate, permitting sole blanks, taps and the like, to be fed into and operated upon by the machine, of varying 50 thicknesses, without resetting or readjustment;—improved means to enable the machine to operate, automatically, upon sole blanks, taps or the like having a large range in varying lengths; novel means to enable the gate and locking mechanism co-operating 55 therewith to be held in predetermined position by devices independent of the grading and indicating means, and for a longer time in the cycle of operation of the machines than has heretofore been possible, thus enabling extremely short stock to be operated upon, mechanism enabling the devices for determining the grade of work to be set and actuated at one spot on the work, and the gate closing instrumentalities to be actuated 60 by another part of the work, together with additional improvements and advantages.

Heretofore in machines of this type, either in the grading and marking machines, or in grading, marking and evening machines, the work, such as a sole blank, tap or the like, is fed through a gate and into the machine by engagement with the feeding rolls. The sole blank also actuated the gate closing device and set the evening 70 knives and grade marking mechanism by engagement with a feeler or feelers upon predetermined portions of the blank, and the passing of the sole out of the machine, opened the gate, permitting a succeeding 75 blank to be fed into the machine. As the marking devices and evening knives were at the rear of the machine, while the feeding and setting mechanism was at the front of the machine, it was most important that the 80 gate actuating devices be accurately controlled so as to prevent a successive blank from entering the machine, until in the cycle of operations, the machine was ready to receive it and in condition to reset the marking and evening mechanism according to 85 the grading of the new blank. My present invention accomplishes the result above briefly explained, and I provide means co-operating with the feeler mechanism to 90 maintain the gate closed even after the blank has passed out of contact with the feelers, thus preventing the gate opening devices to be actuated to open the gate until the proper time and until the machine is ready 95 to receive a successive blank. This mechanism is adjustable, easily rendered operative or inoperative, and is efficient in use, rendering the machine more automatic, and capable of operating upon shorter stock than 100 was formerly possible.

My improved machine also has provision for actuating the feeler mechanism, which

grades the stock and sets the marking, or marking and evening devices, operable upon or by a predetermined portion of the stock, and the gate controlling devices operable upon or by a different part of the stock, although in accord with present practice, and as shown herein, the feeler and hence gate closing device, and the gate opening device are in alignment relatively with the path of travel of stock through the machine.

In order to provide a suitable distance for the gate opening and closing mechanism to allow for the operation of the machine upon soles having a larger variation in thickness than formerly, I provide a recess adjacent the feeler mechanism, and the gate opening member, permitting considerable lift or throw in the gate opening and closing devices, so that a considerably greater distance is traversed thereby.

I have also devised novel mechanism for actuating the marking devices to mark the grade of the stock by stamping thereon at predetermined time during the cycle of operations of the machine, said marking devices being set to the proper marking figure by the actuation of the feeling apparatus and then is automatically actuated or tripped by the stock itself. In the prior constructions of Nichols evening machines, separate feeding rolls were actuated by the stock which could be utilized to trip the stamping devices, but in my present machine for grading and marking, I have greatly simplified the construction, and eliminated the second set of rolls, and therefore it was necessary to devise apparatus which would actuate or trip the stamping and marking devices. I have accomplished this result by automatic means engaged in a predetermined time during travel of the work through the machine, this automatic tripping apparatus being a distinct novelty, and independently of the gate opening mechanism heretofore described.

Other features of the invention, novel combinations of parts and advantages will be hereinafter more fully pointed out and claimed.

Referring to the drawings illustrating a preferred embodiment of the invention as applied to a machine for grading and marking,

Figure 1 is a side view, partly in cross section, of a machine illustrating a preferred embodiment of my invention;

Fig. 2 is a plan view; and

Fig. 3 is a fragmentary cross-sectional view longitudinally through the machine.

The gate controlling mechanism will be first described. As shown in the drawings, a grading and marking machine of the well known Nichols type of said patent is illustrated, wherein the frame 1 has mounted at the forward or receiving end of the machine a pair of feeding rolls 2 and 3, the

lower roll being mounted in sliding journal bearings and normally pressed upwardly by springs, the upper roll being vertically adjustable in its sliding bearings by rotation of the gears 4, 4, engaged by worms 5, 5, 70 on the shaft 6 as in said Nichols Patent No. 1,104,378. The top of the frame 1 is preferably in the form of a table. On the forward portion 7 of said top are lugs 8, 8, at either side of the machine, said lugs forming pivots for the studs 9, 9, carrying the gate 10, said gate carrying a central depending member 11, adapted to rest upon the top of the table 7, when the gate 10 is lowered. This gate is adapted to be raised and lowered on its pivot studs 9, stock being fed thereunder between the adjustable guides 12, 12, during the operation of the machine. A bracket 13 at the front of the machine to receive the stock is usually provided. It is important that this gate be maintained closed, after a piece of stock has been fed into the machine, until the cycle of the machine including the setting of the marking or stamping mechanism and in case of an evening machine of the cutting knives as well, be allowed to perform their respective functions before the succeeding sole is fed into the machine. The gate controlling mechanism therefore, is of great importance. 95 Also it is desirable to have the gate or its member 11, lifted or raised, automatically, a sufficient vertical height to allow the thickest stock on which the machine would operate, to pass thereunder. These two features, i. e., controlling the opening of the gate and also the lift or height to which the gate may thus be opened, constitute, in practice, the limit of speed of operation for the entire machine, the soles being either fed in automatically 100 through the gate or by hand as soon as the opening of the gate permits the succeeding sole to be fed therethrough. By having the depending gate piece 11 hold the gate 10 slightly raised, the side guides for the sole 110 12, 12, may extend underneath the gate and almost directly to the feed rolls 2 and 3, thus guiding the stock into the rolls accurately and in predetermined lateral position.

Cooperating with the feeding rolls 2 and 3 to continue the feeding action on the work, and carry it through the machine, is an endless chain carrier, 15, actuated by sprocket wheels 16 and 17 with the chain projecting through an appropriate slot 18 therefor in the top central portion or bed 19 of the machine. Adjacent the chain carrier 15 and at each side thereof I provide a recessed or deepened portion 20, in said bed, substantially below the normal level 19 and below 125 the top of the carrying chain 15. This recess 20 enables the feeling mechanism or shoe, to be described, to drop a substantial distance below the top of the carrier when the sole is fed completely past the shoe. 130

Secured at one side of the gate 10 is a link 21 pivoted to the gate at 22 and having in its upper portion a slot 23. The forked end of a rock lever 24 extends at either side of the link 21 and a pin 25 passing through the slot 23 retains the forked end of this lever to the link, with the play or lost motion permitted by the length of the slot 23. This rock-lever 24 is pivoted at 26 to a bracket 27 having a pair of upstanding lugs receiving said pivot 26, and the other arm 28 of the rock lever extends beyond said pivot and downwardly as shown at 29, carrying a roll 30 on a stud 31 projecting from the depending portion 29. This roll is in the path of a cam 32 secured to a rockshaft 33, having a locking arm 34 extending at right angles thereto and substantially parallel with the line of travel for the stock, 20 said arm extending approximately midway over the feeding chain 15. The rockshaft 33 is suitably mounted in bearings 35 and 36 extending from a crossbar 37 secured to the machine frame. Between this crossbar 25 and a similar crossbar 38, is a presser foot 40, yieldingly secured to said crossbars by rods 41, 41, normally pressed downwardly by coiled springs 42, 42. This presser holds the stock in firm engagement with the carrier as said stock is slid thereunder in being fed through the machine. Adjustably secured to the arm 34 is a detecting device or shoe 44, having a curved foot 45 adapted to be engaged by the incoming stock and lifted 30 as said stock is fed by the point to which the shoe 44 is adjusted on the arm 34, a set screw 43 holding said shoe in its adjusted position. The lower portion of this detector or shoe is forked to straddle the presser 40 and the carrier chain 15, so that said detector will normally be lowered below the level of the carrying portion of the chain 15 and contact with the bottom of the recess 20. In this position (see Fig. 3) the gate 10 is 40 raised, not only by the weight and leverage of the shoe 44, but by the action of a contractile spring 46, having one end secured to the machine frame and its other end secured to the cam 32. In this position the gate piece 11 is raised and a piece of stock may be fed to the rolls 2 and 3 and from thence on through the machine, raising the presser 40 and striking against the curved beveled faces of the foot 45 of the shoe 44, 45 raising said shoe, lifting the arm 34, releasing the cam 32 from the roll 30 and permitting the gate to drop by gravity, the slot 23 allowing for a still further rocking action in the gate operating lever 24, if necessary. 50 The action of the mechanism responsive to the lifting of the detector or shoe 44, setting the devices for stamping the stock in accordance with the grade determined by said shoe, is similar to that of said prior 55 patents and does not constitute a portion of my present invention. This setting mechanism includes a rack wheel 50 having the racks 51 and 52 thereon, pawls 54 and 53 respectively in position to actuate said wheel to transmit appropriate movement to the marking wheel 55, lock the same in position, and stamp the grade on the stock as determined by the rolls 2 and 3, all in well known manner and as fully described in said prior Nichols patents, excepting so far as the tripping of the devices to bring the stamping wheel 55 down onto the work, my improved and automatic mechanism being one of the features to be herein described. 75

The gate controlling mechanism, as above described, depends for opening and closing, as well as for the extent of throw or lift in the opening and closing action, upon the action of the shoe 44, and as it is desirable to adjust this shoe, longitudinally on the arm 34, for particular work, it frequently happens that, when short stock particularly is being fed through, the stock will be fed past the position of the shoe 44, permitting said shoe to drop and thereby opening the gate, before said stock has traversed the rest of the machine and received its stamping or grade marking, its cutting action, *i. e.*, before the cycle of the machine has been completed, which cycle has been set by the action 95 of the detector mechanism and the pawls and rack wheel in this type of machine. Under such circumstances, therefore, the danger exists that a successive piece of stock being fed in as soon as the gate is opened, 100 would strike the mechanism and detector while the preceding piece of stock was still being acted upon, and therefore the proper operation and function of the machine would be negatived or the parts damaged 105 and broken. To obviate this difficulty, and to enable the machine to operate upon short stock, thus making it more automatic and with the capacity for larger range of work, I provide a device independent of the shoe 44 to control the gate opening operation. To this end I affix a member 60, attaching 110 same to the arm 34 by a clamping nut 61, said device having a forked extension to span the presser 40 and chain 15 and to extend downwardly substantially the same distance as the lowermost portion of the shoe 44, so that both the member 60 and shoe 44 will rest in the recess 20 when in normal position and with the gate open. This member 115 60 may be spaced along the arm 34 at any desired point, in such position as to still maintain contact with the stock fed through the machine after said stock has passed the shoe 44, to still hold the gate 10 closed and thus prevent a successive blank being fed into the machine until the machine is ready to receive it. Consequently the member 60 120 co-operates with the shoe 44, said shoe effecting the raising of the lever 34 thereby con- 125 130

trolling the closing of the gate, because the onward feeding action of the work will cause it to strike the shoe 44 first, and thereupon the member 60 will control the lowering of 5 the lever 34 and consequently the opening of the gate, holding said gate closed long after the stock has passed the shoe 44. It will be readily appreciated that the member 60 is adjustable longitudinally in order to control 10 the gate opening action at any predetermined moment in the operation of the machine, depending upon the length of stock being operated on. It will also be appreciated that this independent gate controlling 15 member may be positioned for contact with the sole blank and actuation thereby at either side of the blank, if desired, as well as on the central portion. A separate bar could be used to carry this gate closing member if desired, but I find it convenient to mount the member 60 on the same arm as that carrying the shoe. The member 60 is adjusted to effect the gate opening actuation of the machine, according to the will of the operator 20 and free and independent of the normal gate opening actuation secured by the shoe 44 alone.

In the machine as herein shown my novel and automatic mechanism for tripping the 30 marker or stamper to mark or stamp upon the sole the grade, number, or the like, in which the machine has found any particular sole to be classed, is actuated by the sole itself. After the sole blank has been fed 35 through the machine until the heel or other portion desired to bear the mark or stamp, has passed through the machine sufficiently so that it is ready to receive the impress of the stamp 55, I provide means for the sole 40 to strike a lever and secure a quick vertical reciprocation of the stamping wheel 55. This tripping mechanism is simple and efficient in construction and automatic in action. The stamping or marking wheel 55 45 is mounted upon a vertically reciprocable post 70 mounted in vertical guideways as is usual in the said Nichols machines. The coiled spring 71 is mounted on a bracket 72 secured to the frame of the machine and 50 normally forces the post 70 carrying the stamping wheel 55 downwardly, to effect the stamping upon the sole. Secured to the side of the frame 1 on a pivotal mounting at 73 is a lever 74, the top of said lever 55 75 having a shoulder to engage a trip member 76, the vertical face 77 of the top of said lever being held normally in contact with a stop 78 secured to the frame, through the tension of the spring 79 having one end 60 attached to the arm 80 on said lever and the other end secured to a pin 81 on the frame. On this lever 74 is a lug 82, in position where it is in contact with the short arm 83 on a rockshaft 84, the other or long arm 85 also 65 secured to the rockshaft, having an upstand-

ing portion 86 provided with a beveled face 87 projecting in the path of the sole blank as the same is fed through the machine by the carrier 15. I prefer to form the upstanding end 86 of this lever as a forked 70 member having corresponding beveled faces 87 on each, as clearly shown in Fig. 2, which forked end projects above and overlaps the correspondingly reduced end part 91 of the presser member 40 (see Fig. 3). The sole 75 blank when fed between the presser 40 and the carrier 15 thus is compelled to engage the beveled faces 87, forcing downwardly the lever 85, turning the rockshaft 84 and thereby causing the short arm 83 to rock the 80 lever 74 against the tension of its spring 79 and disengaging the end 75 from the trip member 76. Releasing the member 76 permits a clutch, of any suitable type, to connect the gear 92 on the shaft 93, which actuates the chain of gears 94, 95 and 96, the latter being formed with a cam to release the post 70, permit the spring 71 to force said post downwardly until the stamping wheel 55 engages the work, as it passes thereunder, and thereupon the cam of said gear 96 again engages the post 70 and raises it 90 against the pressure of its spring 71, holding it in position for the second reciprocation, the clutch actuating this train of gears 95 being automatically disconnected after a single revolution by the action of the stud 66 on the brake 97, disconnecting the clutch, all as shown in the prior Nichols patents.

My automatic tripping mechanism is so arranged that the beveled faces 87 may be projected in the path of the sole blank at any desired point, thus permitting the sole blank to actuate the tripping mechanism and effect the stamping of the sole by the 100 wheel 55 at any desired point. As herein shown, the tripping device is so positioned as to effect the stamping on the sole immediately after the heel or forwardly moving part of the sole has passed under the stamping wheel 55, the post 70 thereupon effecting its reciprocation and stamping the sole between the figure or number on the bottom of the wheel and the anvil 100. It will be appreciated, however, that I may arrange the 110 tripping lever 85 of suitable length so that the sole might be fed almost entirely through and out of the machine, before the stamping thereon. In case, for example, it was desired to stamp the mark, grade, trademark 120 or other insignia carried by the wheel 55 and post 70 on the toe portion, shank or other part of the sole, my present invention contemplates the feasibility of such results. As the capability of my novel tripping mechanism is of wide and general 125 scope, I wish to claim the same broadly.

Having already described the operation of the gate controlling mechanism and of the tripping mechanism, it will be appreciated 130

that while both these devices operate in synchronism herein, it is feasible to utilize either device when desired, in machines of this type, particularly when the machine includes 5 evening mechanism, or cutting knives. The inclusion of the tripping mechanism, however, in a machine for grading and marking only, enables an extremely simple and efficient mechanism to effect the marking, and 10 at any predetermined point in the path of travel of the work, rendering the combination of the gate controlling and tripping devices to be peculiarly beneficial in a simple and efficient machine for grading and marking, making this machine much more automatic than has been possible heretofore.

My invention is further described and defined in the form of claims as follows.

1. A machine of the kind described, adapted to operate on stock, comprising stock feeding means, a gate adapted to close when the stock is fed therethrough, stock grading devices, automatic mechanism to mark the stock controlled by said grading devices, and 25 a plurality of stock engaging means to hold the gate closed, until a predetermined time in the cycle of operations of the machine.

2. A machine of the kind described, adapted to operate on stock, comprising stock feeding means, a gate adapted to close when the stock is fed therethrough, stock grading devices, automatic mechanism to mark the stock controlled by said grading devices and an independently adjustable member engaging 35 the stock after said stock has passed from contact with the grading devices to hold the gate closed, until a predetermined time in the cycle of operations of the machine.

3. A machine of the kind described, adapted to operate on stock, comprising stock feeding means, a gate adapted to close when the stock is fed therethrough, stock engaging devices, automatic mechanism to mark 40 the stock controlled by said engaging devices, means actuated by the stock to close the gate, and a member controlling the open-

ing of the gate independently of the action of said gate closing means, said means being actuated by the forwardly moving end 50 of the stock to close the gate, and said independent member being actuated by the complete passage of the stock to open the gate.

4. A machine of the class described, adapted to operate on stock, comprising feeding 55 mechanism to feed the stock through the machine, a movable gate, means to control the opening and closing of said gate actuated by the stock during its feeding action, said gate controlling means including a plurality of stock engaging devices adapted for controlling action by the stock at different points on the stock.

5. A machine of the class described adapted to operate on stock, comprising means to 65 carry the stock through the machine, a movable gate positioned in advance of the stock feeding means, gate controlling devices arranged over the path of said stock feeding means, and adapted to be actuated by the 70 stock fed therethrough, said machine having recesses below the carrier, and said gate controlling means including a shoe adapted to rest upon the top of the stock and to drop below the carrier into said recess to produce 75 a greater vertical moving action on the gate than the maximum thickness of stock fed through the machine.

6. A machine of the class described, adapted to grade and mark stock, comprising feeding means, grade detecting mechanism arranged for detecting the thin spot in a predetermined portion of said stock, means for marking the grade so detected, locking mechanism to hold the marking means in the position to which it is adjusted by the detecting mechanism, in combination with additional stock engaging devices, operative after the stock has passed from the detecting mechanism to maintain the mechanism as actuated by said detecting mechanism.

In testimony whereof, I have signed my name to this specification.

LEANDER A. COGSWELL.
